FACE PANEL FOR A CONTROL INSTRUMENT

Ronald C. Miller, Norristown, Pa., assignor to Honeywell
Inc., Minneapolis, Minn., a corporation of Delaware

Filed Aug. 11, 1966, Ser. No. 3,428

Term of patent 14 years

(Cl. D52—6)

The figure is a right, front perspective view of a face panel for a control instrument, showing my new design.

The reverse side of the control instrument face is conventional.

I claim:

The ornamental design for a face panel for a control instrument, substantially as shown and described.
